ABSTRACT: In order to minimize the obstacles on the deck surrounding a hatch opening adapted to be covered by side-wards rolling cover sections, fixed wheels are arranged on the coaming and on pillars outside the coaming, respectively, and located in lines forming extensions of two parallel sides of the coaming. Each section is at two sides being parallel to the moving direction, provided with a downwardly directed side portion extending along, but at some distance from the pertaining side of the coaming, mechanically operated sealing members being arranged to bridge the gap between such a downwardly directed portion and the adjacent side of the coaming.

HATCH COVER OF THE SIDE-ROLLING TYPE

This application contains subject matter disclosed in applicants' prior application Ser. No. 712,989 filed Mar. 14, 1968 (now abandoned) and constitutes a division of said application.

Many hatch covers consist of sections which may be moved in a horizontal plane towards and away from each other and thus be made to cover and to open, respectively, an opening in the deck of a ship or the roof of a building. Hatch covers of this type are usually called side-rolling covers, and the sections are in open position supported by means arranged outside the coaming surrounding the opening. These means may be fixed to the cover sections or they may form elongations of two sides of the hatch coaming. Means of the first-mentioned type are liable to be damaged during the opening and closing movements and means of the last-mentioned type will form a limitation to the possibilities of transport on the deck transversely to the opening direction when the cover is closed. Side-rolling hatch covers of this type have been provided with wheels or rollers which have been adapted to run on guideways on the coaming. Usually two cooperating sections are utilized but on occasion a single section may be utilized and sometimes also more than two sections may come into the picture.

SUMMARY OF THE INVENTION

The present invention refers to a hatch cover where each section in open position is carried by supports outside the coaming and it is characterized in the wheels adapted to facilitate the movement of the cover being mounted on the coaming and on supports outside the coaming consisting of pillars being arranged in lines forming extension of two parallel sides of the coaming and so located in relation to the length of the cover section to be moved that the point of gravity of said cover during this movement will always be located between two pillars in each line.

With covers carried by wheels it is necessary to provide means, which make possible a lowering of the section, when the same is to be closed, in order to obtain the desired sealing against the coaming. In hitherto known designs it has therefore been necessary to lower and to lift respectively the total weight of the cover to obtain and to break the contact with the packing. During the voyage of a ship the weight of the coaming rests on the packing and to this weight the force of the seas washing over the deck will be added. According to a further development of the invention the packings are relieved of these extra strains and may be designed solely for the sealing purpose.

BRIEF DESCRIPTION OF THE DRAWINGS

FIG. 1 shows schematically a view of one embodiment of the member;

FIG. 2 shows a cross section of a detail along line II-II in FIG. 1 and on a somewhat enlarged scale;

FIG. 3 shows a section corresponding to that in FIG. 2 at a modified embodiment;

FIG. 4 shows a section along line IV-IV in FIG. 3;

FIG. 5 shows a section corresponding to that in FIG. 2 at a further modified embodiment; and

FIG. 6 shows a detail at one of the pillars contained in FIG. 1.

DESCRIPTION OF THE PREFERRED EMBODIMENTS

The hatch opening is surrounded by a coaming 1 on which two cover sections 2 and 3 rest in closed position and are movable in the horizontal plane to open the same. The operation of the sections may be brought about by a suitable apparatus of known design, not shown here.

Two sides of the coaming, here called the transverse sides, are provided with a number of rollers 4 which carry the sections and facilitate the movement thereof. A number of pillars 5 are arranged in lines forming elongations of the transverse

sides of the coaming. Each pillar carries a roller 6 at its top part. These pillars are so located and have such a height above the deck in relation to the length of the cover section that the point of gravity of a section will always be located between two pillars in each line. In this manner it is possible to prevent the outermost edge of the section to tilt downwards before it reaches the next pair of pillars. The cover section is thus always carried in the horizontal plane and no lifting thereof will be called for.

The pillars make possible transportation along the coaming when the cover is closed and preferably the distance between the outermost pillars in each line is such that it will be possible to utilize a fork lift truck or similar vehicle. The normal distance between the pillars is chosen to provide adequate support for the section but in order to guarantee that the same will not tilt downwards during the movement to the outermost pillars where the distance may have to be close to the practical limit, it may be appropriate as shown in FIG. 6 to provide the pillars located close to the hatch opening with means for instance further rollers 45, cooperating with the top side of the section to keep the innermost part of the cover section downwards.

The cross section of FIG. 2 shows that the coaming is provided with an upper flange 7. The cover section 2 has such a breadth that it reaches outside this flange and is provided with a downwardly directed portion 8. This carries an upper flange 9 and a pair of lower flanges 10 and 11, respectively. The upper flange 9 at the cover section as well as flange 7 on the coaming is each provided with a downwardly directed ledge 12 and 13, respectively. These ledges are adapted to cooperate with a packing 14 which is carried by a channel bar 15 running along the side of the coaming. This channel bar is connected to a number of hydraulic rams 16 carried by the lower flange 10 and which by means of a conduit 17 are connected to a common source of fluid under pressure. When the cover is closed the packing may be brought into contact with the two ledges 12 and 13, respectively, in such a manner that a satisfactory sealing is obtained. Conduit 17 may be provided with valve means to maintain the pressure at the rams during the time it is desired to keep the sealing forced against the ledges. When the pressure at the rams is relieved the sealing means are withdrawn by means of springs 18. The lower part of the side portion 8 is provided with a governing edge 19 which cooperates with the rollers 4 and 6, respectively. The longitudinal sides of the sections are designed principally in the same manner as indicated in FIG. 2, i.e. in closed position the side of the section will reach below flange 7 in the coaming and the channel bar 15 may be applied in a corresponding manner.

In the embodiment shown in FIGS. 3 and 4 parts corresponding to those in FIG. 1 are denoted by the same numerals. The coaming 1 is thus provided with a flange 7 which has a downwardly directed flange 13. Section 2 is provided with a downwardly directed side portion 8 and this is provided with a first flange 9 cooperating with the flange 7 at the coaming as well as with lower flange 11. The section is also provided with a guiding edge 19 for cooperation with the rollers 4 and 6, respectively. Also in this embodiment a channel bar 15 carrying a packing 14 for cooperation with ledges 12 and 13 in flanges 9 and 7, respectively, is provided. In this case, however, the rams 29 which are provided with pressure fluid by means of a conduit 27 are arranged above the packing and are adapted to pull the latter against the ledges at the flanges. Springs 28 will force the packing away from the ledges when the rams are relieved of pressure.

The rams are mounted on flange 29 in the cover section 8 and a yoke 30 enclosing the ram is connected to a bar 31 running along the channel bar carrying the packing. The ram will pull the yoke upwards and the spring 28 is arranged between the yoke and a support 32 at the cover section. The packing means are governed in relation to the section by a number of pegs 33 which run in openings in the lower flange 11 at the section. In both embodiments the packing is nor-

mally free from the flanges in such a manner that a displacement of the sections may be brought about. The rams must then always be supplied with pressure fluid. It is of course possible to operate in the reverse manner i.e. to have strong springs adapted to pull or to push the packing against the flanges. This may easily be done as in these designs the packing never will have to carry the weight of the cover. The rams will then be utilized only on those occasions when it is desirable to move the sections.

Such an embodiment is shown in FIG. 5. Section 2 is also here provided with a downwardly extending portion 8 carrying a flange 9. The coaming is provided with an outwardly directed flange 7 in which the rollers 4 are mounted. The governing edge 19 of the cover section as well as flange 9 will thus be located above flange 7.

The sealing arrangement here includes two packings 35 and 36, respectively, of which the first-mentioned is attached to the section at the joint between the downwardly directed portion and the flange 9. The other packing 36 is located on the movable sealing member 15. This is designed as an inverted U-beam the shanks of which have different length. The shorter shank 37 serves as an abutment against packing 35 whereas the other longer shank 38 is designed as a mounting for packing 36. Flange 7 is connected to the main part of the coaming somewhat below the upper edge thereof in such a manner that a ledge 39 for cooperation with packing 36 is obtained. The channel forming the packing mounting on shank 38 is provided with a number of downwardly directed pegs 40 which in closed position cooperate with correspondingly shaped openings in flange 7 in such a manner that the sealing member cannot unintentionally be pushed sideways. The sealing member is by means of a number of strong springs 18 to be brought to cooperate with the sealing ledges at the section and at the coaming, respectively, and may be lifted therefrom by means of pressure fluid operated rams 16.

We claim:

1. In a hatch cover a coaming surrounding an opening and at least one cover section movable in the horizontal plane in relation to said coaming to open and to close said opening, respectively,
- 5 an outwardly directed flange at each of the two sides of the coaming parallel to the direction of movement of the cover section,
- 10 a downwardly directed portion at each pertaining side of the cover section running parallel to the adjacent flange of the coaming to form an elongated gap between said flange and said downwardly directed portion, a sealing member running along said gap, and mechanical means including compression springs forcing said sealing member towards edge portions of said flange, at opposite sides of said gap, as well as fluid-operated rams for temporarily breaking the sealing contact during operation of the covers.
- 15 2. A hatch cover according to claim 1 in which the flange at the coaming as well as the downwardly directed portion of the cover section is each provided with a downwardly directed portion of the cover section is each provided with a downwardly directed ledge serving as abutment for a single-packing element in the seating member.
- 20 3. A hatch cover according to claim 1 as utilized with covers where the lower edge of the downwardly directed portion is designed as a governing rail cooperating with wheels carried by the coaming, and in which an inwardly directed flange at the cover section is arranged on a higher level than the flange in the juxtaposed side of the coaming, the improvement of the sealing member comprising two separate strips of packing material, one of the packing strips, preferably the outermost one, being fixed to the flange at the cover, whereas the other strip, preferably the innermost one, is fixed to the sealing member.

UNITED STATES PATENT OFFICE
CERTIFICATE OF CORRECTION

Patent No. 3,602,183 Dated August 31, 1971

Inventor(s) Reinhard Olai Aarvold and Erik Holger Isaksson

It is certified that error appears in the above-identified patent and that said Letters Patent are hereby corrected as shown below:

In Claim 2, lines 4 and 5, the words
"portion of the cover section is each provided
with a downwardly directed" are repeated
twice and should be deleted.

Signed and sealed this 27th day of June 1972.
